INVENTOR.

Robert Monsch
Charles L. Wright
ATTORNEY

UNITED STATES PATENT OFFICE.

ROBERT MONSCH, OF UNION CITY, NEW JERSEY.

INCLINABLE WINDOW.

Application filed January 18, 1926. Serial No. 82,021.

This invention relates to improvements in window construction as applied to dwelling houses, office buildings and the like and has as one of its objects the provision of a window sash pivoted to swing outward between a pair of stiles, slidably within the sash within the window frame, the axis of the sash being at its extreme lower edge.

5 A further feature is to provide a swinging sash so arranged in connection with its sliding stiles that the latter are positively maintained in proper adjusted position, inseparably from the sash.

10 Another aim is to produce a swinging sash having spring counterbalancing means whereby muscular effort in moving the sash upon its pivot is materially reduced.

15 A still further object is to provide spring actuated catches to retain the sash when closed between its stiles, these catches being arranged in such manner as to prevent release of the sash except by use of both hands of an operator and are substantially inoperable by children.

20 25 These several valuable objects are accomplished by the novel and practical construction of parts hereinafter described and delineated in the drawing, forming an essential part of this disclosure, and in which:—

30 Figure 1 is a partial front elevational, partial sectional view showing a corner of a window made in accordance with the invention.

35 Figure 2 is a sectional view taken on line 2—2 of Figure 1.

Figure 3 is another view like Figure 1, illustrating a modification in construction.

Figure 4 is a view similar to Figure 1 showing a further modification of the same.

40 Figure 5 is a sectional view taken on line 5—5 of Figure 4.

Figure 6 is another front and sectional view in which a further adaptation of the device is shown and also the latch connecting the sash and stiles.

45 Figure 7 is a fragmentary view showing an alternative type of sash and stile engaging means.

Throughout the several views a transparent window pane, such as glass, is designated by the numeral 10, the same being secured by usual glazing methods in a sash frame 11 of ordinary construction except that its side members are rabbeted lengthwise at their rear outer edges, as best seen

in Figure 7, to engage the correspondingly projecting tenon-like elements 12 of a pair of stiles 13 one on each side of the sash and equivalent in length therewith.

The stiles 13 are slidable between guide 60 cleats 14 secured in pairs on the inner surfaces of the window frame side members 15, which are connected at their upper and lower ends to the upper rail beam and sill respectively of the window.

65 A simple form of the device is shown in Figures 1 and 2, in which the lower member of the sash is formed with a longitudinal groove 16 at the center of its width, the groove registering with similar grooves 17 in the lower ends of the stiles 13.

70 A rod 18 of circular cross section is disposed in these grooves and retained therein by a flat sheet metal plate 19 held to the lower edge of the sash by fastenings 20.

75 The ends of the rods 18 are flattened and bent at right angles, as at 21, to fit into corresponding grooves formed centrally in the outer sides of the stiles 13 where they are secured by screws 22.

80 It will now be seen that the rod 18 acts as a hinge element on which the window sash may pivot when swung forward, also as a connecting member between the sash and stiles, and further, maintains the stiles in 85 proper spaced relation, besides causing them to positively move up and down in conformity with any sliding movement imparted to the window sash.

85 90 Substantially the same arrangement is indicated in Figure 3 except in place of the groove 18, a groove 23 is formed of increased sectional area, and the rod 18 is encircled by a pair of oppositely wound torsional springs 24, their inner adjacent ends 25 being secured in the plate 19 and their outer ends 26 set in the lower ends of the stiles 13, the effect being to exert pressure on the sash to move it into a closed position, as will be understood.

95 100 In a similar manner the device shown in Figs. 4 and 5 acts to normally close the sash against the abutments 12 of the stiles.

105 In this case grooves 27 are formed in the lower member of the sash frame at each end and disposed therein are torsional springs 28, retained by the plate 19, the inner ends 29 of the springs being fixed in the sash and the outer ends 30 being similarly fixed in the stiles 13.

In this device the axes of the springs correspond with the pivotal axis of the sash and the springs not only serve as hinge members, but normally press the sash into closed

5 position, and in addition the tension of the springs act to draw the stiles against the sides of the sash.

Figures 6 and 7 show a structure incorporating the features of Figures 3, 4 and 5 10 in addition to others of practical merit.

In this case the sash is grooved its full length, as at 31, and disposed therein are oppositely wound torsional springs 32 and 33 retained by the plate 19 as previously 15 described.

The inner ends 34 are loosely inserted into an opening 35 at the center of the sash and their outer ends 36 bent at right angles to pass into recesses 37 in the outer faces of the 20 stiles and be held rigidly therein by clips 38.

In this case the springs perform a three-fold duty; to act as a hinge element, to close or assist closing the sash, and to retain the stiles and sash in intimate contact.

25 These last named figures also show a pair of catches designed to hold the sash when in a closed position and prevent inadvertent opening of the same.

These catches are composed of a flat strip 30 40 provided with lugs 41 held in the upper member of the sash frame by a pivot 42. At the inner ends of these strips are knobs 43 by which the catches may be tilted on their pivots, the sash being cut out for that purpose and compression springs 44, set in the 35 sash, retain the catches in operative position.

Near the outer ends of the strips, on their undersides, are detents 45 to engage in appropriate 40 openings in the upper ends of the stiles, over which the strips extend.

These detents are bevelled on their rear, engaging sides, so that when the sash is closed against the stiles, the catches will rise 45 until complete closure has been effected, whereupon the springs 40 will force the detents into engaging position.

It will be seen that in order to release the sash from the stiles, that is to swing the sash 50 forward, both catches must be manipulated requiring the use of both hands, thus reducing accidental loosening of the sash, and also that the knobs 43 serve as handles by which the sash may be readily drawn forward.

Obviously the springs will be suited to the weight and type of the window and may be used only as buffers, partially counter- 60 acting the forward movement of the sash, or be sufficiently strong to close the same with little or no effort on the part of an operator.

While certain preferred embodiments of 65 this device have been shown and described, it will be understood that changes in the

form, arrangements, proportions, sizes and details thereof may be made without departing from the scope of the invention as defined in the appended claims.

Having thus described my invention, what 70 I claim as new and desire to secure by Letters Patent, is:—

1. In a window, the combination with a window frame having vertical cleat guides on their proximate faces, stiles slidable between said guides, said guides having in-reaching longitudinal flanges at their rear edges, a sash adapted to seat between said stiles against flanges, said sash having a longitudinal round bottomed groove in its 80 lowermost member, a rod disposed in said groove, means to retain the rod therein, said rod extending below said stiles, right angularly bent terminals at the ends of said rods, and means to secure said terminals to 85 the outer faces of said stiles.

2. In a window, the combination with a window frame having vertical guides on their proximate surfaces, stiles operable between pairs of said guides, a window sash disposed between said stiles, said sash having a longitudinal round bottomed groove throughout its lower member, a rod disposed in the groove to extend below the ends of 90 said stiles, a plate to retain said rod within the groove, means on the ends of said rods to fixedly engage said stiles and torsion springs encircling said rod, one end of each spring being anchored in said plate and the other end fixed in said stiles.

3. In a window, the combination with the frame thereof, a pair of stiles slidably engaged with said frame, a sash disposed between said stiles, co-operative means between said stiles and sash to prevent swinging movement of the sash in one direction, means to retain said stiles in fixed relation to the sash, and torsion springs carried in the lower member of the sash, said springs being anchored at their ends respectively in 100 the sash and stiles.

4. In a window, the combination with the frame thereof, a pair of stiles slidably engaged with said frame, a sash disposed between said stiles, co-operative means between said stiles and sash to prevent swinging movement of the sash in one direction, said sash having a longitudinal groove extending throughout its lower member, torsional springs disposed in said groove, the inner ends of said springs being anchored in the sash, their outer ends being bent at right angles to enter recesses in said stiles, means to secure the outer ends of the springs to said stiles, and a plate on said sash to cover the groove and retain the springs therein.

5. In a window, the combination with the frame thereof, a pair of stiles slidably engaged with said frame, a sash disposed be-

tween said stiles, co-operative means between said stiles and sash to prevent swinging movement of the sash in one direction, means to retain said stiles in fixed relation to the sash, a pair of spring hinges uniting said sash and stiles, means for securing the springs to said sash, other means to secure the outer ends of the springs to the stiles whereby the sash and stiles may be raised and lowered as a unit, and catches to retain the sash and stiles in operative relation. 10

In testimony whereof I have signed my name to this application.

ROBERT MONSCH.
